UNITED STATES PATENT OFFICE.

JAMES M. BUTCHER, OF CHICAGO, ILLINOIS, ASSIGNOR TO WILLIAM L. ROHRER, OF CHICAGO, ILLINOIS.

PORTABLE BURGLAR-ALARM.

1,241,484.

Specification of Letters Patent. Patented Sept. 25, 1917.

Application filed November 23, 1914. Serial No. 873,631.

To all whom it may concern:

Be it known that I, JAMES M. BUTCHER, a citizen of the United States, residing at Chicago, in the county of Cook and State 5 of Illinois, have invented certain new and useful Improvements in Portable Burglar-Alarms, of which the following is a specification.

This invention relates to improvements in 10 alarms and has for its principal object to provide an improved alarm of the portable type which may be conveniently used by travelers or other persons to warn them of attempted entrance into their rooms. More 15 particularly my invention comprises an alarm adapted to be attached to the shank of a door knob and of such construction that the turning of the door knob in either direction will cause an alarm to be given. Further 20 features relate to the means for readily assembling and adjusting the parts and to the simplicity of structure whereby the alarm is inexpensive in cost and efficient in operation.

25 Other features and objects of the invention will be set forth in the following specification taken in connection with the accompanying drawings which illustrate a specific embodiment of the invention.

30 In the drawings;

Figure 1 shows a front elevation of the alarm attached to a door knob shank which is shown in section;

Fig. 2 shows a side elevation of the alarm 35 attached to the shank of a door knob; part of the bell casing being broken away.

Fig. 3 shows a rear elevation of the alarm.

Referring to the drawings, the numeral 10 40 designates a bell which may be employed to give the alarm. This bell is of a type well known in which there is an operating member which operates normally to prevent the ringing of the bell and upon the release of which the bell is permitted to ring, as I term 45 it, continuously, that is, for a considerable period of time. A bell of this type is spring actuated and is wound up by rotating the cap portion of the bell with respect to its base, but since the bell is well known, and I 50 do not claim any particular form of bell, I give no detailed description thereof.

The operating or check member of the

bell is designated by the numeral 11 and is in the form of a spring secured to a rigid part of the bell. When this spring is 55 pressed inwardly with respect to the bell it causes the bell to ring, but when released it returns automatically to its normal position in which it prevents the bell from ringing.

The bell 10 is supported by a standard 12 60 which is provided with slots 13 extending longitudinally thereof to be engaged by screws 14 which enter suitable threaded apertures in the rear face of the bell casing. The standard 12 is pivoted at its upper end 65 to the lower angularly disposed portion 15^a of a clamp member 15, the pivotal connection being made by a pin 16 secured to the clamp member and engaging a slot 17 in the standard 12. An enlarged aperture 18 70 communicates with the slot 17 and permits the standard 12 to be readily disengaged from the clamp member 15 by moving said standard upwardly until the head of the pin 16 registers with the aperture 18. 75

The upper extremity of the clamp member 15 is provided with an enlarged head 15^b which is threaded to be engaged by the thumb screw 19 having the knurled head 20. The lower extremity of the thumb screw 19 80 85 pivotally engages a clamping shoe 21 which is provided with an arcuate surface oppositely disposed with reference to an arcuate surface 15^c on the portion 15^a of the clamp member. The arcuate surfaces just described are adapted to coact with the shank 22 of a door knob 23 and it will be apparent that the thumb screw 19 may be manipulated to rigidly secure the clamp member 15 90 to said door knob shank.

The operating or check member 11 is actuated to ring the bell by means of an actuating member 24, the lower end of which is offset at 24^a to enter the bell casing and contact with said operating member. The 95 actuating member 24 is reciprocably mounted upon the clamp member 15 by means of a rectangular slot 25 which is engaged by a lug 26 formed integrally with or attached to the portion 15^a of the clamp member and which is provided with overlapping ears 27 100 adapted to engage the outer surface of the actuating member adjacent the slot 25. The lug 26 has a lower plane surface 26^a which

normally coacts with the lower wall of the slot 25 and the actuating member 24 is normally maintained in this position with respect to the lug 26 by the action of the 5 spring operating member 11. When the clamp member rotates with respect to the standard 12, however, the lug 26 causes the actuating member 24 to move downwardly with respect to the clamp member, thereby 10 pressing the operating member 11 downwardly and permitting the bell to ring. The angular movement of the clamp member with respect to the standard 12 is limited by the lug 15^a formed on the rear face 15 of the portion 15^a of said clamp member.

The clamp member having been rigidly secured to the shank of a door knob, it will be seen that the weight of the bell 10 will operate to normally maintain the standard 12 in a vertical position, but when the shank 20 22 of the door knob is turned in either direction, this tendency of the bell 10 to maintain the standard 12 in a vertical position will operate to cause a relative angular movement of the clamp member with respect to said standard. This angular movement, as above explained, will cause the lug 26 to coact with the lower wall of the slot 25, thereby moving the actuating member 24 25 downwardly and giving an alarm.

It will be evident that this device may be readily attached to the shank of any door knob, and that the parts thereof are very simple and easily assembled. The bell 10 30 may be adjusted with respect to the standard 12 in order to regulate the sensitiveness of the alarm by sliding the screws 14 in the slots 13, and if desired, the standard 12 may be removed from the clamp member 15 in 35 the manner above described.

From the above description it will be apparent that I have provided a convenient and efficient form of alarm which may be readily attached to the shank of a door knob to be actuated by the rotation of the door 40 knob in either direction.

While the form shown in the drawings is the one now preferred by me, it will be understood that I contemplate changes in 45 form and arrangement of parts as circumstances may suggest or necessity require without departing from the spirit of my invention as defined by the appended claims.

I claim:—

- 55 1. An alarm, comprising a bell having an operating member, a standard by which said bell is carried, a clamp member to which the standard is pivoted, and an actuating member for operating said operating member, said actuating member being reciprocably mounted on and supported by said clamp member and arranged to be actuated by the rotation of said clamp member with respect to said standard.
- 60 2. An alarm, comprising a bell having an

operating member, a standard by which said bell is carried, a clamp member to which the standard is pivoted, and an actuating member engaging said operating member, said actuating member being provided with a rectangular slot and said clamp member being provided with a part to engage said slot and support said actuating member. 70

3. An alarm, comprising a bell having an operating member, a standard by which said bell is carried, a clamp member to which the standard is pivoted, and an actuating member engaging said operating member, said actuating member being provided with a rectangular slot and said clamp member being provided with a part to engage said slot and support said actuating member, said operating member being adapted to maintain said actuating member in normal relation to said clamp member. 75 80

4. In an alarm, the combination of a bell having an operating member, a standard by which said bell is carried, a clamp member to which said standard is pivoted and which is adapted to be secured to the shank of a door knob, and an actuating member arranged to engage said operating member and reciprocably mounted on said clamp member, whereby when said shank is rotated in either direction the weight of said bell will tend to maintain said standard in a vertical position and thereby cause said actuating member to ring said bell. 90 95

5. In an alarm, a bell having an operating member, a standard by which said bell is carried, a clamp member on which the standard is pivoted, an actuating member engaging said operating member and operatively connected to said clamp member to be operated by a relative angular movement of said clamp member and said standard, and supporting means carried by said clamp member for limiting the angular movement of said standard. 100 105

6. In an alarm, a bell having an operating member, a standard by which said bell is carried, a clamp member to which the standard is pivoted, an actuating member engaging said operating member, said actuating member being provided with a rectangular slot, and a lug projecting from said clamp member and engaging one wall of said slot, said lug having projecting parts to prevent displacement of said actuating member from said clamp member and being arranged to effect the operation of said actuating member when said standard moves angularly with respect to said clamp member. 110 115 120

7. In an alarm, a bell having an operating member, a standard by which said bell is carried, a clamp member upon which said standard is detachably and pivotally mounted, a reciprocable actuating member engaging said operating member and slidably 125 130

mounted on said clamp member to effect
the operation of said operating member
upon relative angular movement of said
standard and said clamp member, and
5 means to adjust said bell with respect to
said standard to regulate the operation of
said actuating member.

In testimony whereof, I have subscribed
my name.

JAMES M. BUTCHER.
